UNITED STATES PATENT OFFICE

2,598,410

SPOTTING APPARATUS

James E. Miller, Syracuse, N. Y., assignor to Dryco Corporation, Syracuse, N. Y., a corporation of New York

Application October 13, 1949, Serial No. 121,091

8 Claims. (Cl. 299—83)

1

This invention relates to a spotting apparatus for use in commercial dry-cleaning establishments and the like.

Various apparatus of this type have heretofore been proposed which are of such construction as to require the operator to manipulate the various valves incorporated therein by either foot or hand-operated levers. The apparent disadvantage of this construction is that the area of operation of the spotting tool by the operator is restricted to the reach of the operator with respect to the valve levers. In instances where a large piece of cloth is being cleaned, this disadvantage presents a somewhat awkward situation. To overcome this disadvantage, some apparatus have been proposed wherein the control valve itself is incorporated in the spotting tool; however, this arrangement is very unsatisfactory because the tool becomes unduly heavy and is thus fatiguing to the operator and it also is hazardous to the operator because a full head of steam is required at all times at the tool and, thus, a break in the hose connecting the tool to the steam separator would result in severe injury to the operator.

Thus, it is one of the objects of this invention to provide a spotting apparatus whose area of effective operation is greatly increased.

It is a further object of this invention to provide an apparatus wherein the controls for the operation of the various valves of the apparatus are conveniently mounted on the spotting tool itself without greatly increasing the weight of the tool or endangering the operator.

It is a further object of this invention to provide an apparatus whereby the valves for the steam, water, and dry air are remotely controlled by the operator from the spotting tool.

It is still a further object of this invention to provide an apparatus which is simple in construction and effective in operation.

Further and additional objects will appear from the description, accompanying drawings, and appended claims.

In accordance with one embodiment of this invention, a spotting apparatus is provided comprising a steam separator unit having outlet ports for steam, water, and dry air, and a chamber associated with said separator unit and common to said outlet ports. Operatively connected to the chamber is a spotting tool. Associated with each of the outlet ports is a valve which is remotely controlled by means mounted on the spotting tool.

For a more complete understanding of this invention reference should now be had to the drawings wherein:

Fig. 1 is a front elevational view of the spotting

2

apparatus showing a top plan view of the spotting tool.

Fig. 2 is a side elevational view of the spotting apparatus showing a top plan view of the spotting tool.

Fig. 3 is a fragmentary sectional view of the separator unit, associated valves, and chamber taken along line 3—3 of Fig. 1.

Fig. 4 is a fragmentary sectional front elevational view of the separator unit.

Fig. 5 is a fragmentary sectional view of the spotting tool showing one of the valve control switches mounted thereon.

Fig. 6 is a circuit diagram of the electrical system for the apparatus.

Referring now to the drawings and, more particularly, to Fig. 1, a spotting apparatus is shown comprising a steam-spotting unit 10, a plurality of valves 11, 12, and 13 mounted thereon, and a chamber 14 associated with said separator unit and common to said valves.

Operatively connected to the output side 15 of chamber 14, by means of a flexible tube or hose 16 of predetermined length, is a spotting gun or tool 17, from which is emitted the output from the separator unit 10.

The separator unit 10, as shown more completely in Figs. 3 and 4, is provided with a steam cavity 18 and a dry air cavity 20. The steam cavity 18 is provided at its upper end with outlet ports 21 and 22, said ports being respectively the steam outlet port and the water outlet port. Openings 23 and 24 are formed in one side of the steam cavity 18 in order to allow live steam to be circulated therein. The live steam is fed into the cavity through the upper opening 23 and, after circulating through the cavity, is removed through opening 24. The steam, while circulating in the cavity, causes condensate 25 to be collected in the lower portion of the cavity as shown in Fig. 4. The opening 24 acts as an outlet for any overflow condensate in the cavity. Secured at one end to water outlet port 22 is a pipe or conduit 26, having the other end thereof terminating in the lower portion of the cavity and submerged in the condensate 25. Considerable pressure is created in the steam cavity 10 by the circulating steam. Thus, when it is desirable to have water fed from the cavity through outlet port 22, the pressure causes the condensate 25 to flow up through pipe 26 and out through port 22.

Formed in the lower portion of air cavity 20 is an air inlet port 27, through which dry air is fed into the cavity 20 and caused to flow upwardly and out through the outlet port 28 formed at the upper end of cavity 20. The air cavity 20 is

separated from the steam cavity 18 by a wall or partition 30 which has a high heat transfer coefficient. Thus, the heat of the steam within cavity 18 causes the air chamber to be likewise heated. A coil spring 31 or other similar type element is placed within the cavity 20, as shown in Fig. 4, and serves as a baffle whereby turbulent flow is created in the cavity and effects greater heat absorption by the air. The spring 31 is held in position within the cavity 20 by means of a bushing 32 which is threaded into the outlet port 28.

The valves 11, 12, and 13 are connected by suitable fittings 33 to outlets ports 28, 21, and 22, respectively. All valves are of a conventional type having a valve stem 34 mounted within the valve housing 39 and adapted to normally remain closed. The upper end 35 of the stem is exposed and is actuated by a lever 36 which is pivotally mounted at point 37 to a bracket 38 which, in turn, is mounted on the valve housing 39, as shown in Fig. 3. The lever 36 for valve 13, as shown in Fig. 2, is actuated by a conventional type alternating current solenoid 40, disposed above valve 13 and mounted on a suitable support 49. A similar support 49 is mounted on the valve housings for valves 11 and 12. The solenoid 40 is actuated by a relay, not shown, which is disposed within a box 41 which is mounted by suitable connections 42 on the steam separator unit 10, as seen in Fig. 2. Relay leads 43, 44, and 45 extend from box 41 to solenoids 40, 46, and 47, respectively. The solenoids 46 and 47 perform the same function for valves 11 and 12, respectively, as solenoid 40 for valve 13 as hereinbefore described and are actuated by individual relays enclosed within box 41. A fourth lead 48 from box 41 extends to the spotting tool or gun 17 and is connected to switches 50 and 51 mounted on said tool. A low voltage transformer T, not shown, is enclosed within box 41 and is connected with the relays as shown in the circuit diagram Fig. 6.

Control switches 50 and 51 mounted on the spotting tool are of the conventional button type. As shown in Fig. 5, the switch 50 comprises a button 52 which is slidably mounted in a suitable opening formed in the handle 53 and is normally held in its up position by leaf contact 54. A shoulder 55 formed in the lower portion of button 52 prevents the button from becoming disengaged from the opening provided in handle 53. The operator upon depressing button 52 causes leaf 54 to come in contact with leaf 56 positioned therebeneath. Upon contact being made, the circuit is closed to the relay designated R₁ enclosed within box 41 which, in turn, causes solenoid 46 to be actuated whereby valve 12 is opened and steam is caused to flow through outlet port 21, into chamber 14, through flexible tube 16, and out through nozzle 59 of tool 17. Upon further depressing of button 52 by the operator, leaf 56 is caused to make contact with leaf 57 formed therebeneath, and a second relay, designated R₂ in Fig. 6, is caused to be actuated and solenoid 40 energized. Valve 13 is then opened and water or condensate 25 is caused to be emitted from separator 10. The steam valves 12 and 13, when button 52 is fully depressed, are both open and steam and water are caused to mix together in chamber 14 and a wet steam pass through tube 16 and out through nozzle 59. The switch 50 is fastened by means of screws 58 to the handle 53, which is constructed of a heat insulating material and surrounds the nozzle

59 of spotting tool 17. Switch 51 which is adjacent switch 50 is of like construction. Upon depressing of the button 60 of switch 51, a contact is made closing the circuit for relay R₃ which is enclosed within box 41, thereby causing solenoid 47 to be energized and valve 11 made to open; thus allowing hot dry air to flow from separator unit 10 and to be emitted from the spotting tool 17.

The procedure followed by the operator in manipulating the apparatus is as follows: (a) The end 61 of the nozzle 59 of tool 17 is positioned above the soiled portion of the garment and the switch 50 partially depressed by the operator, causing steam to be emitted from the end 61 of nozzle 59; (b) if greater moisture is required to remove the spot, the operator fully depresses the button 52 of switch 50, thereby causing a wet steam to be emitted from the end 61; and (c) after the spot has been successfully removed the operator releases button 52 and then the steamed portion of the garment is dried by the operator depressing button 60 of switch 51, causing hot dry air to be directed onto the garment.

A simplified circuit diagram of the electrical system for the apparatus is shown in Fig. 6. The low voltage transformer T is connected to a suitable power supply. When the circuit to relay R₁ is closed by partial depressing of button 52, the contact 62 in the circuit for solenoid 46 is closed, thereby causing the solenoid 46 to be energized. Upon further depressing button 52, the relays R₁ and R₂ are placed in parallel combination with one another, and both solenoids 46 and 40 are energized. Upon release of button 52, the circuits to relays R₁ and R₂ are broken; the contacts 62 and 63 for solenoids 46 and 40, respectively, are opened; and valves 12 and 13 resume their normal closed position. Upon depressing button 60 of switch 51, the circuit to relay R₃ is closed whereupon the relay is actuated causing contact 64 to close the circuit to solenoid 47. Upon release of the button 60, the circuit for solenoid 47 is broken and the valve 11 once again is closed.

It will be obvious that certain modifications of the specific embodiment shown may be made without departing from the spirit and scope of this invention. For example, an individual switch for each relay R₁, R₂, and R₃ may be mounted on the spotting tool 17 so that each of the valves 11, 12, and 13 may be operated independently of the other. In certain other instances where it is believed that the drying of the garment is not a necessary operation the switch 51 mounted on the tool 17 may be omitted and the valve 11 manually actuated if required by a hand or foot pedal.

It will thus be seen that a spotting apparatus has been provided which enables the area of operation with a spotting tool to be greatly increased. Also, the operation of the valves for the separator unit may be remotely controlled by the operator at the spotting tool without the tool becoming unduly heavy or the operator being exposed to the danger of a full head of steam at the spotting tool.

While a particular embodiment of this invention is shown above, it will be understood, of course, that the invention is not to be limited thereto since many modifications may be made and it is contemplated, therefore, by the appended claims, to cover any such modifications as fall within the true spirit and scope of this invention.

I claim:

1. An apparatus of the class described comprising a steam separator unit provided with outlet ports, a chamber associated with said unit and common to said outlet ports, a spotting tool operatively connected to said chamber, and a control member mounted on said tool and operatively connected to said unit for regulating the output of said unit through said ports.

2. An apparatus of the class described comprising a stationary steam separator unit provided with valved outlet ports, a chamber associated with said unit and common to said outlet ports, a movable spotting tool operatively connected to said chamber, and a control member mounted on said tool and operatively connected to said valved ports for regulating the output of said unit through said ports.

3. An apparatus of the class described comprising a stationary steam separator unit having a steam outlet port, a water outlet port, and a dry air outlet port, a control valve for each of said ports, a chamber associated with said unit and common to said ports, a movable spotting tool operatively connected to said chamber, and a control member mounted on said tool for actuating said valves.

4. An apparatus of the class described comprising a steam separator unit provided with outlet ports, a chamber associated with said unit and common to the outlet ports thereof, a spotting tool operatively connected to said chamber, and a control member mounted on said tool and operatively connected to said unit for regulating the output of said unit through said ports; said separator unit comprising a steam cavity through which steam is circulated, the condensate from said steam being collected in said cavity, a steam outlet port formed in said cavity and operatively connected to said chamber, an outlet port for said condensate formed in said cavity and operatively connected to said chamber, a dry air cavity adjacent said steam cavity, air intake and outlet ports formed in said air cavity, said air outlet port being operatively connected to said chamber, and means for increasing the heating action of said air while circulating through said air cavity.

5. An apparatus of the class described comprising a steam separator unit having outlet ports for steam, water, and dry air, a chamber associated with said unit and common to said outlet ports, a control valve for each of said ports, a solenoid for actuating each of said valves, a relay for actuating each of said solenoids, a spotting tool operatively connected to the outlet side of said chamber.

ber, and means mounted on said tool for controlling the operation of said relays.

6. An apparatus of the class described comprising a steam separator unit having outlet ports for steam, water, and dry air, a chamber associated with said unit and common to said outlet ports, a control valve for each of said ports, solenoids mounted on said unit for actuating the control valves for said water and steam outlet ports, relays mounted on said unit for actuating said solenoids, a spotting tool operatively connected to the outlet side of said chamber, and a finger switch mounted on said tool; said steam valve relay adapted to be energized upon partial closing of said finger switch whereupon only steam is emitted from said tool, and both said steam and water relays adapted to be energized upon said switch being fully closed whereupon a mixture of steam and water is emitted from said tool.

7. An apparatus of the class described comprising a relatively stationary steam separator unit provided with outlet ports, a chamber associated with said unit and common to said outlet ports, a spotting tool operatively connected to the outlet side of said chamber and movable relative to said chamber and unit, and a control member mounted on said tool and operatively connected to said unit for regulating the output of said unit through one outlet port or through more than one of said outlet ports simultaneously.

8. An apparatus of the class described comprising a steam separator unit having outlet ports for steam, water, and dry air, a chamber associated with said unit and common to said outlet ports, a control valve for each of said outlet ports, a spotting tool operatively connected to the outlet side of said chamber, and controls mounted on said tool and operatively connected to said valves for remotely operating said valves independently or in combination with one another.
